UNITED STATES PATENT OFFICE.

SYVERT JOSTEN, OF SEATTLE, WASHINGTON.

PAVING-BLOCK CONSTRUCTION.

1,183,070.

Specification of Letters Patent.

Patented May 16, 1916.

Application filed June 15, 1914. Serial No. 845,274.

To all whom it may concern:

Be it known that I, SYVERT JOSTEN, a citizen of the United States, residing at Seattle, in the county of King and State of Washington, have invented certain new and useful Improvements in Paving-Block Construction, of which the following is a specification.

This invention relates to the subject of paving blocks, and has special reference to a novel form and combination of road-bed and gutter-forming blocks.

The primary object of the present invention is to provide a substantial and thoroughly practical road-bed construction by a novel combination and arrangement of road-bed blocks and curb and gutter blocks, each of which is formed with novel interlocking and overlapping joint portions, which because of their simplicity greatly facilitate the laying of the road-bed and consequently present many advantages, chief among which is time and labor saving.

A further object of the invention is to provide a construction of this character wherein all of the blocks are laid so that the possibility of one block sinking below the other is reduced to a minimum, thereby producing a road surface that is not only firm and durable when first laid, but which increases in solidity under the weight of continuous traffic.

With the above and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawings, in which—

Figure 1 is a transverse sectional view of a road-bed constructed of the blocks forming the present invention. Fig. 2 is a plan view showing two rows of blocks laid in road-bed formation. Fig. 3 is a perspective view of one of the gutter-and-curb-forming blocks. Fig. 4 is a perspective view of one of the road-bed blocks.

Similar reference characters designate corresponding parts in the several figures of the drawings.

In carrying out the present invention, it is preferable to use a composition block which comprises a base of concrete and a surface of

asphaltum which has embedded therein coarse gravel or stone, though it will of course be understood that any desired material or composition that is capable of being molded, and which is possessed of sufficient wear resisting qualities may be used to a practical advantage. However, the slabs comprising the elements referred to provide an unusually durable road surface which has all of the desirable traction characteristics, namely, permanency, elasticity, and a non-skidding surface, and for this reason their embodiment in the slabs contemplated by the present invention is preferred.

Regardless of the kind of material that is used in the blocks, they always have the same structural characteristics which may be best observed in detail in Figs. 3 and 4 of the drawings, wherein the reference numeral 1 designates the combination gutter and curb forming block in its entirety, while the rectangular road-bed block unit is designated by the reference numeral 2.

With special reference to the combination gutter and curb blocks 1, it will be observed that each of the same comprises a body portion which has formed at one side of its upper surface a flat curb face 3, and at its opposite side is provided with a flat gutter face 4 which meets at an angle with an upwardly inclined gutter face 5 terminating at the outer edge of the curb face 3. The said blocks 1 are preferably elongated and formed at one end with a projecting substantially inverted T-shaped tenon 6, while the opposite end thereof is provided with a complementary angular-end mortise 7 which is similar in configuration to the angular projecting tenon. The vertical side 8 of the block 1 is arranged to form a supporting abutment for the sidewalk material, while the opposite side 9 is formed into an offset anchor flange which projects from the body of the block to provide a locking joint shoulder 10.

The road-bed blocks 2 shown in Fig. 4 of the drawings are of such a construction that they may be placed in position to form the road-bed, by being laid upon either of their flat faces. That is to say, these blocks are reversible so that when they are used with either one of their flat faces exposed, the same interlocking and overlapping with adjoining slabs is accomplished. Each of these blocks 2 essentially comprises verti-

cally disaligned rectangular members 11 and 12, which disalignment produces projecting flange portions 13 and 14 on opposite sides of the block. In other words, this arrangement produces locking joint shoulders 15 on all sides of the block, which shoulders are all in the same horizontal plane, though it will be obvious that the flanges projecting from the lower member of the block will 5 always underlie flanges on an adjacent block, while the flanges projecting from the upper member of the block will always overlap with the lower flanges of an adjacent block. Thus, this construction provides two 10 sides of the block with a joint shoulder which lies beneath an overlapping joint shoulder of two adjacent blocks, and also provides the two opposite sides of the block with a joint shoulder which overlaps with 15 joint shoulders of two adjacent blocks, thereby producing a very effective locking of one block with another and at the same time presenting a joint which tends to support adjoining slabs. In connection with 20 the laying of these road-bed blocks 2, it is preferable to place each of the same so that the center of the road-bed is raised high enough to produce a water-shed, or each of the blocks may be made with a sufficient 25 curve to accomplish this result in a more pronounced manner. In either event, this construction forms an arch which rests against the interlocking curb blocks so that any weight placed upon the center 30 would have a tendency to bear toward the sides causing the outer edges of the curb blocks to be pushed farther down into the ground, and at the same time more firmly 35 uniting all of the overlapping portions of 40 the road-bed blocks.

With further reference to the combination curb-and-gutter blocks 1, it will be observed that the body of the same may be varied in width so that the gutter face 4 is wider than 45 that shown in Fig. 3 of the drawings, but even with the increased width of the body of the curb block, the anchor flange 9 and joint shoulder 10 are always preserved. The widened curb block is shown in Fig. 2, 50 and also in Fig. 1, and it will be understood that the reason for this variation in width is solely to adapt the blocks to the particular width of the road bed being constructed.

From the foregoing description, it is believed that the method of constructing the 55 blocks forming the subject of the present in-

vention, and the manner of laying the same will be readily apparent. However, in this connection it may be said that after the road-bed has been graded according to the 60 specifications of the road, the curb blocks are put in position so that their side faces 65 form an abutment for the sidewalk material S, while the tenon ends 6 are laid so that they fit into the angular mortise 7 of the 70 next adjoining block. When the curb blocks are laid in this fashion, a continuous joint shoulder 10 is produced which is adapted to receive thereon one of the joint shoulders 15 of the road-bed blocks 2 so that 75 the upper face of the latter is flush with the flat gutter face 4 of the curb block. The laying of the curb and road-bed blocks may be carried on indefinitely, in each instance 80 the curb blocks interlocking with each other at their ends while the side of the same which is provided with a joint shoulder engages with one of the road-bed blocks. Each of the latter blocks or slabs have two 85 of their projecting portions overlapping with locking joints of an adjoining block, and also two of their projecting portions held down by two adjoining blocks as previously mentioned, thus forming the complete road-bed. 90

I claim:

A paving construction including a gutter section formed by a series of interlocking combination curb - and - gutter forming blocks, each comprising a body portion provided with a flat gutter face and a flat curb face at different levels, and a flat inclined gutter face connecting said curb and gutter faces, said blocks also having at one end a projecting tenon comprising a horizontal 95 portion and an intermediate vertically extending portion, and having at the opposite end an angular end mortise similar in configuration to the said projecting tenon, the edge of said body below the flat gutter face 100 being laterally off-set to form a locking shoulder which merges with the projecting horizontal portions of the said tenon, and road-bed blocks engaging with said shoulder of the combined curb-and-gutter forming 105 blocks.

In testimony whereof I hereunto affix my signature in the presence of two witnesses.

SYVERT JOSTEN.
